OTHER PUBLICATIONS

Low power wearable systems, published online May 26, 2016 at dx.doi.org, site visited May 1, 2022, available online at: <https://ieeexplore.ieee.org/document/7479442> (Year: 2016).*

Primary Examiner — Catherine Ho(74) *Attorney, Agent, or Firm* — Leavitt Eldredge Law Firm(57) **CLAIM**

The ornamental design for a wearable advertisement device, as shown and described.

DESCRIPTION

FIG. 1 is a perspective view of a wearable advertisement device according to my new design.

FIG. 2 is a left view of the wearable advertisement device.

FIG. 3 is a right view of the wearable advertisement device.

FIG. 4 is a perspective view of the wearable advertisement device in an alternate position.

FIG. 5 is a top view of the wearable advertisement device.

FIG. 6 is a bottom view of the wearable advertisement device; and,

FIG. 7 is an exploded top perspective view of the wearable advertisement device.
